[57] CLAIM

The ornamental design for a communion cup dispenser
or similar article, as shown and described.

DESCRIPTION

FIG. 1 is a right side elevational view of a communion
cup dispenser or similar article showing my new design, with the undisclosed left side being a mirror image and the broken-line showing of the cup being for illustrative purposes only and forming no part of the claimed design;

FIG. 2 is a rear elevational view thereof;

FIG. 3 is a bottom plan view thereof;

FIG. 4 is a top plan view thereof; and,

FIG. 5 is a front elevational view thereof.
